UNITED STATES PATENT OFFICE.

GUY ARTHUR, OF SPOKANE, WASHINGTON, ASSIGNOR TO ARTHUR-FOWLER CO., OF SPOKANE, WASHINGTON, A CORPORATION OF WASHINGTON.

RANGE-BOILER COVER.

Application filed November 8, 1923. Serial No. 673,623.

To all whom it may concern:

Be it known that I, GUY ARTHUR, a citizen of the United States, residing at Spokane, in the county of Spokane and State of Washington, have invented new and useful Improvements in Range-Boiler Covers, of which the following is a specification.

This invention relates to improvements in heat insulating covers for range boilers.

One feature of my invention is to provide a cover in sections, preferably half sections which may be attached to and detached from the boiler, and in the most preferred embodiment of my invention, the cover is split 15 into longitudinal sections.

Some range boilers are welded and have continuously smooth peripheries while other boilers are riveted and have at the top and bottom an annular row of rivet heads and 20 also a longitudinally extending line of rivet heads. My invention is designed for either type of boiler. These boilers are not absolutely uniform in diameter, as regards given sizes, any one size varying up to one 25 half an inch in diameter. Now it will be clear that in either the riveted type or welded type there would always be a slight space between the cover and the boiler through which air would circulate as it is necessary, from a manufacturing standpoint, 30 to make the sections of a slightly larger size, or over size, for the reason that the edges must abut, and for the further reason that a given or stock size of cover will vary slightly 35 from the size which it should be. Thus, there is a variation in both the boilers and the covers.

Now it is a feature of my invention to provide the cover sections with radially inwardly extending shoulders adapted not only to seat on the upper edge of the boiler and close the intervening space, but also to function as supports for the cover sections to hold the latter in proper vertical relation 45 to the boiler not only during but after installation is made.

It is now common practice to employ a band-like or patch-like electric heater to boilers of this type, and of course these 50 heaters project from the periphery of the boiler to which they are applied. Now it is a feature of my invention to prevent what would otherwise be a bulge in the cover, by recessing the latter on the interior of the 55 sections in order to accommodate these heat-

ers and at the same time afford a uniform diameter and appearance on the exterior of the cover.

It is important to insulate the top area of the boiler against heat radiation, in addition to the periphery thereof, and because of the pipe connections and the crown-like curvature of the boiler top, it has been the practice to employ an initially plastic material such as magnesite, which when hard, 60 forms a most effective insulation against heat radiation. Now in order to prevent the inwardly projecting shoulder of my improved cover from adhering to the insulation on top of the boiler, I face the shoulder with a material which will not adhere to the magnesite or other plastic material used, whereby the sections of my cover may be removed at any time to repair the heater 65 without disrupting the hardened plastic material.

The device of my invention has many other features which will be more fully described in connection with the accompanying drawing and which will be more particularly pointed out in and by the appended 70 claims.

In the drawing:

Fig. 1, is a view in side elevation showing one form of my improved cover applied to a riveted range boiler, the cover being in section.

Fig. 2, is an enlarged sectional view of the upper end of the boiler showing more clearly the overhanging shoulder.

Fig. 3, is a fragmentary sectional view of the boiler and cover illustrating the manner in which the electric heater is accommodated.

Fig. 4, is a perspective view of one section of the improved cover.

Fig. 5, is a sectional view on line 5—5 of Fig. 2.

Like characters of reference designate similar parts throughout the different figures of the drawing.

I have shown my invention applied to a riveted range boiler designated at 1, having upper and lower annular rows of projecting rivet heads 2 and 3. A longitudinal row of projecting rivet heads is shown at 4. The head 5, of the boiler is secured by the upper row of rivets and laps the interior of the boiler 1, thereby leaving an exterior annular shoulder 6. A similar shoulder is also afforded on the welded boilers. The usual 105 110

pipes 7, extend through the head 5, and this fact, together with the fact that the top 5 is rounded, presents certain difficulties in insulating the top with any kind of a formed material. I therefore employ an initially plastic material, such as magnesite, as indicated at 8. The material is applied in a plastic condition so that after it hardens, the area of the top is fully covered and effectively insulated against heat radiation.

While the device of my invention is applicable to tanks or boilers not equipped with electric water heaters, I have shown the boiler 1 with a band-like heater 9, applied circumferentially thereto, in the usual way and in the usual elevation with respect to the height of the boiler. It will be clear that the heater 9 will project from the periphery of the boiler a distance equal to the thickness of the heater, as will be clearly seen in Fig. 3. The heater is vertically located on the boiler in accordance with the height of the column of hot water desired, the location shown, being the usual one, as stated.

My improved cover is shown formed of two longitudinal sections, one of which is shown detached in Fig. 4. Each section is shown provided with an inwardly projecting ledge or shoulder 10, at the top thereof. The inner wall 11, of said shoulder is faced with a non-adhering substance such as oiled paper, 12, or the like. Abreast of the usual position of an electric heater, the cover sections are recessed as indicated at 13 to form an annular chamber. Because of the fact that these heaters vary in size, I do not make this recessed feature with a view of causing the cover to support the heater by engaging the same either below, above or on the periphery of the heater. In fact I make the recess larger than the largest heater so that there will be some space between the recessed walls of the cover and the heater, as shown in Fig. 3. By reason of the annular chamber, it will be seen that the cover sections may be installed and the heater accommodated irrespective of the circumferential location of the cover sections with respect to the heater.

When the half sections are fitted to the boiler, they are first disposed about the same and are hung onto the boiler by means of the engagement of the shoulders 10, with the top edge 6. This serves to support the cover sections while the latter are bound by any suitable means such as a sheet metal band so as to dispose the edges 14, in tight abutting contact. I have shown a metal band at 15, in Fig. 5.

Now because of the fact that the cover sections cannot be made absolutely accurately, and because of variation in size of the boilers as regards diameter, I make the cover sections slightly over size so that

when they are applied to a boiler, and tightened with a band or other means, the edges 14, of the two sections will always be in tight abutting contact. Hence, there will be a certain amount of space between the interior of the cover and the periphery of the boiler. If this space were open at the top, the air would be heated and would rise and new air or cold air would enter at the bottom, as designated at 16. This circulation of air would of course result in loss of heat, thereby cutting down the efficiency of the cover. However, with the shoulder 10, tightly engaging the edge 6, the escape of air upwardly through the top is cut off, and whatever air is between the cover and boiler is not circulating and hence does not cause any loss of efficiency. The space which is present between the cover and boiler on a riveted boiler, is generally no greater than on a welded boiler. However, it will be noted that the projecting rivets extending annularly and longitudinally of the boiler, would prevent perfect contact of a cover with the boiler unless the cover was bendable or flexible, as in the case of a blanket, and even then, perfect contact could not be obtained.

My improved cover is to all intents and purposes a rigid structure without any appreciable flexibility. In practice, the cover is made in the form of a cylinder and later sawed into two separate sections as shown. I preferably employ what is known as corrugated paper, which is rolled to form and all abutting areas glued thereby making the finished structure substantially rigid. The thickness of the finished cover is about three inches. Now the corrugated paper is arranged to dispose the corrugations lengthwise of the cover, or in other words, vertically disposed when the cover is installed. Thus, there is formed or provided a multitude of longitudinal air spaces 17, running vertically through the cover. I consider it a feature of the invention to close these spaces at the upper end of the cover, and I preferably do this by applying an initially plastic material such as magnesite, as shown at 18. Enough is applied so that some will run down the spaces to some extent thereby ensuring complete closure. I may say that the extension 19, is built onto the cover and is preferably of the same material and is likewise closed to prevent circulation in the same manner. Now when the cover sections are first placed in position, the extension 19, forms a wall about the top 5, into which the plastic material 8 is disposed. After the same, hardens, it is possible to readily remove the cover sections without disrupting the hardened magnesite, thereby avoiding what would otherwise be necessary repairs to the same.

In addition to recessing the cover at 13, 130

to accommodate the heater 9, I also insulate the cover from the heater so that in case the heater is effected by atmospheric disturbances, the paper cover cannot be ignited. 5 To this end, I apply a thickness of initially plastic magnesite to the walls of the recessed portion 13, as shown at 20, 21 and 22. Now it will be clear that as regards the radially innermost series of air spaces in the 10 cover, the same will be closed not only at the top by the material indicated at 18, but also near their lower ends, by the material 20. Thus, for the effective height of the 15 column of hot water, that is above the heater 9, the innermost spaces will be entirely closed. This renders the insulation against radiation still more effective. As regards the innermost spaces closed by the material 21, this is not of such great importance because these spaces are abreast of the cold area of the boiler 1.

It is believed that my invention will be fully understood from the foregoing description and while I have herein shown one 25 specific form of my invention, I do not wish to be limited thereto except for such limitations as the claims may import.

I claim:—

1. A cover for a range boiler having peripherally projecting rivet heads near its 30 top and bottom and longitudinally thereof, comprising in combination, longitudinal cover half sections shaped to be disposed about and peripherally enclose the boiler, means for holding said sections against the rivet heads of said boiler, and said sections having semi-annular and inwardly projecting and supporting shoulders overhanging and engaging the top end of said boiler and 35 thereby preventing air circulation between the periphery of said boiler and the interior of said cover.

2. A cover for a range boiler having peripherally projecting rivet heads near its 40 top and bottom and equipped with a band-like water heater, comprising in combination, longitudinal cover half sections shaped to be disposed about and peripherally enclose the boiler, said sections being semi-annularly recessed to extend about the water 45 heater, means for holding said sections against the rivet heads of said boiler, and said sections having inwardly projecting supporting shoulders overhanging and engaging the top end of said boiler and thereby preventing air circulation between the periphery of said boiler and the interior of 50 said cover.

3. A range boiler cover comprising, cover

sections adapted to be disposed about and peripherally house the boiler, said sections being made up of laminated material having air spaces extending longitudinally of said cover, and means for closing said air spaces 65 at the top of said cover to prevent circulation of air through said spaces.

4. As a means of covering a range boiler, a sectional cover peripherally housing the boiler substantially throughout the height thereof, the upper portion of said cover extending above the top edge of said boiler and having a radially inward extension forming a downwardly facing supporting shoulder overhanging and seating on the top edge of 70 said boiler and also forming an annular wall 75 surrounding the top of said boiler, an initially plastic material covering the top of said boiler and filling the space within said annular wall, and said annular wall having a non-adhering facing to prevent the plastic material from adhering thereto, whereby said cover sections may be removed without disrupting said material.

5. A range boiler equipped with a band-like heater, in combination with a cover 80 made up of laminations having air spaces extending longitudinally of said cover, said cover having an internally recessed portion 85 to accommodate said heater, means facing said recessed portion and closing the adjacent terminals of the radially innermost series of air spaces, and means for closing the top of said cover whereby said innermost series of air spaces will contain only dead 90 air.

6. A range boiler cover comprising, cover sections adapted to be disposed about and peripherally house the boiler, said sections being formed of a material having air spaces, and said sections having supporting shoulders engaging the top edge of the boiler to prevent air circulation between the cover and the periphery of the boiler.

7. A range boiler comprising, substantially rigid cover sections formed of heat insulating material and adapted to be disposed about a boiler to house the latter, and said sections having supporting shoulders adapted to engage the top of said boiler to support the sections while the latter are being 105 and after the same are installed, and said shoulders closing the top of the intervening space between the installed cover and the periphery of said boiler.

In testimony that I claim the foregoing as my own, I hereby affix my signature.

GUY ARTHUR.
